[57] CLAIM

The ornamental design for a mobile radiotelephone apparatus, as shown and described.

DESCRIPTION

FIG. 1 is a front plan view of the mobile radiotelephone apparatus of the present invention;

FIG. 2 is a back plan view of the mobile radiotelephone apparatus of FIG. 1;

FIG. 3 is a left side view of the mobile radiotelephone apparatus of FIG. 1;

FIG. 4 is a right side view of the mobile radiotelephone apparatus of FIG. 1;

FIG. 5 is a bottom end view of the mobile radiotelephone apparatus of FIG. 1; and,

FIG. 6 is a top end view of the mobile radiotelephone apparatus of FIG. 1.

1 Claim, 1 Drawing Sheet
